BIRD WHISTLE

James R. Becker, 200 5th Ave., Kings Point, N.Y.
10010, and Herman Kesler, A-102 Cedarbrook Hill
Apts., Greenwood Ave. and Limekiln Pike, Wyncote,
Pa. 19095

Filed June 7, 1971, Ser. No. 150,885

Term of patent 14 years

Int. Cl. D21—01
U.S. Cl. D34—15

FIG. 1 is a front elevational view of a bird whistle showing my new design;

FIG. 2 is a side elevational view thereof, the other side being similar;

FIG. 3 is a rear elevational view thereof;

FIG. 4 is a top plan view thereof;

FIG. 5 is a bottom plan view thereof; and

FIG. 6 is a side elevational view showing another embodiment wherein a larger crowned hat is employed and the facial portion has a larger eye.

We claim:

The ornamental design for a bird whistle, substantially as shown and described.
